UNITED STATES PATENT OFFICE.

ANDREW P. ANDERSON, OF NEW YORK, N. Y., ASSIGNOR OF ONE-HALF TO
JOHN DAHLGREN, OF NEW YORK, N. Y.

ELECTRIC SWITCH.

SPECIFICATION forming part of Letters Patent No. 703,515, dated July 1, 1902.

Application filed June 6, 1901. Serial No. 63,361. (No model.)

To all whom it may concern:

Be it known that I, ANDREW P. ANDERSON, residing at New York, in the county of New York and State of New York, have invented 5 certain new and useful Improvements in Electric Switches, of which the following is a full, clear, and exact description, such as will enable others skilled in the art to which it appertains to make and use the same.

10 My invention relates to electric switches of the oscillating mechanical cut-out type; and an object of my improvement is to provide a mounting for the contact knives or blades of such a switch whereby good contact at all 15 times is insured and the knives will be held in any position in which they may be placed, thereby preventing an accidental throwing of the switch.

10 My invention consists, further, in certain 20 features of construction and combinations of elements, as will be fully set forth hereinafter and the novel features of which will be pointed out in the claims at the end of this specification.

25 In the drawings, Figure 1 is a plan view of my improved switch. Fig. 2 is a side elevation thereof, showing in dotted lines the switch in open position. Fig. 3 is a section taken on the line xx , Fig. 1.

30 Similar characters refer to similar parts throughout the several views.

A is an insulating base-plate; B B, leading-in binding-posts; C C, contact-springs or anvils, and D D represent generally supporting-uprights for the contact-knives. These 35 parts are of the usual and well-known construction.

It will be understood that the anvils C and the supporting-uprights D are of slightly-reduced 40 silent conducting material. Each upright D is made up of two standards 1 1, supported upon a suitable base having a binding-post thereon. Through said standards 1 1 passes the bolt 2, having the end of its shank screw-threaded for the reception of the locking-nut 3, which may be turned on to clamp the standards together in the usual way. Washers 4 4 may be interposed, if desired. At the 45 point where the screw-threads of the shank or bolt 2 begin said shank is reduced in diameter to form an annular shoulder 5, whereby

the inner locking movement of nut 3 is limited. The head of bolt 2 is flanged or turned over, as at 6, thereby forming between said flange and the shank of the bolt an annular 55 groove or recess, within which is located a spiral spring 7, one end of which bears against the inner side of the head of the bolt and the other end against the adjacent standard 1 or against a washer, if such is used. The knives 60 or blades 8 8 are pivoted between standards 1 1 upon the bolt 2, and said knives are connected by bridges 9 and 10 of suitable insulating material, the bridge 9 connecting the outer ends of the knives and the bridge 10 connecting them intermediate of their lengths. The handle 11 has shank 12, which passes through both of these bridges and is held in position by screw 13 or other means, as desired.

The operation is in general like that of other 70 switches of this class. When the knives are thrown down by the handle 11 between the anvils C C, the circuit is closed, and when they are thrown up it is broken. The advantages of my structure result in the first 75 place from the second bridge 10, which, in conjunction with bridge 9 and the shank 12, passing through both bridges, forms a strong and rigid framework, whereby buckling of the knives is prevented at a point between 80 the pivots thereof and the anvils. Such buckling is often liable to occur in a construction of this class wherein a single bridge is used, and it will be readily seen that such buckling will prevent the free movement of 85 the knives between the anvils C. This defect is entirely done away with by my construction.

In the usual construction, wherein a nut upon a pivot-bolt is alone relied upon to force 90 together the two standards between which the knives are held, if good contact is to be secured such nut must be turned on very tight. This necessitates a strong pull upon the handle in order to throw the switch, and friction 95 and strain between the various parts result. On the other hand, if the nut is left comparatively loose, so that the knives move easily between the standards, contact secured between the knives and standards is not so good, and 100 if the switch were then left in the position shown in dotted lines in Fig. 2 it could be easily

jarred down therefrom and accidental contact ensue. My provision of a shoulder upon the pivot-bolt, so that the clamping movement of the nut is limited, and the provision of a 5 spring for forcing the two standards together to grip the contact-knife yieldingly therebetween result in a structure having these further advantages that good contact is insured between the parts, a comparatively small 10 amount of force is needed to throw the switch, so that there is no friction or strain between the parts, and yet the grip of the standards upon the knives is such that the switch will be held in any position in which it may be left, 15 as in the dotted-line position shown in Fig. 2, without danger of an accidental closing of the circuit.

It will be obvious that the spring might be located either, as shown, between the head of 20 the bolt and its adjacent standard or between the nut and its adjacent standard. So far as the location of the spring is concerned either 25 end of the bolt may be considered the head, and where in the claims I use the term "head of the bolt" I intend such term in its broad- 30 est acceptation. The provision of a flange to form a housing for the spring provides a construction such that the spring is kept free from dirt and is out of the way and provides 35 in general a more compact, workmanlike, durable, and efficient structure.

It will be obvious that the construction shown in Fig. 3 may be applied to one or both of the uprights of any given switch, such as 35 that shown in Fig. 1, that the screw-threaded nut upon the end of the bolt may be dispensed with, a washer and locking-pin taking its place, the spring alone being depended upon for adjusting the pressure of the stand-

ards upon the knife, and that various changes 40 in minor details may be made without departing from the spirit of my invention.

What I claim as new, and desire to secure by Letters Patent, is—

1. In an electric switch, in combination, a 45 contact-knife, a standard upon which said knife is pivotally mounted upon a bolt passing through said standard, an inwardly-extending flange upon the head of said bolt, a 50 spring located in the recess formed by said flange and adapted to hold the knife yieldingly to its standard and a nut for said bolt.

2. In an electric switch, in combination, the supporting-standards 1, 1, the bolt 2 having its head flanged at 6, spring 7 located in the recess formed by said flange and adapted to bear 55 against one of said standards, nut 3 for said bolt, a contact-knife pivoted upon said bolt between said standards, and an anvil C, or other contact means, substantially as de- 60 scribed.

3. In an electric switch, in combination, the supporting-standards 1 1, the bolt 2 having its head flanged at 6 and having a shoulder 5, 65 a nut 3 adapted to bear against the shoulder 5 upon said bolt, spring 7 located in the recess formed by said flange 6 and adapted to bear against one of said standards, a contact-knife pivoted upon said bolt between said standards, and an anvil C or other contact 70 means, substantially as described.

In testimony whereof I affix my signature in the presence of two witnesses.

ANDREW P. ANDERSON.
